(57) **CLAIM**

The ornamental design for a dietary supplement packaging indicium, as shown and described.

DESCRIPTION

FIG. 1 is a perspective view of the new design;
FIG. 2 is a front view of the new design;
FIG. 3 is a right side view of the new design;
FIG. 4 is a rear view of the new design;
FIG. 5 is a left side view of the new design;
FIG. 6 is a top view of the new design;
FIG. 7 is a bottom view of the new design;
FIG. 8 is a perspective view of an alternate embodiment of the new design;
FIG. 9 is a front view of an alternate embodiment of the new design;
FIG. 10 is a right side view of an alternate embodiment of the new design;
FIG. 11 is a rear view of an alternate embodiment of the new design;
FIG. 12 is a left side view of an alternate embodiment of the new design;
FIG. 13 is a top view of an alternate embodiment of the new design; and,
FIG. 14 is a bottom view of an alternate embodiment of the new design.
Dashed lines represent environmental context and form no part of the claimed design.
